Attorneys.

Patented May 26, 1925.

UNITED STATES PATENT OFFICE.

JAMES HUBERT, OF NEWCASTLE-UPON-TYNE, ENGLAND.

EXERCISING APPARATUS.

Application filed June 7, 1924. Serial No. 718,522.

To all whom it may concern:

Be it known that I, JAMES HUBERT, a subject of the King of Great Britain and Ireland, residing at Byker, in the city and county of Newcastle-upon-Tyne, England, have invented certain new and useful Improvements in Exercising Apparatus, of which the following is a specification, reference being had therein to the accompanying drawing.

This invention relates to exercising apparatus, and has for its object to provide an improved construction which will be strong and can be cheaply manufactured.

15 Exercising apparatus according to my invention comprises one or more strips of rubber or other elastic material attached at their ends to suspending members which may be provided with hand grips or may engage wall hooks or the like, the means of attachment comprising a clamp embracing the suspending member and a cylindrical block fixed at the end of the rubber strip, which block may be moulded in one with the strip 20 or formed by two semi-cylindrical blocks cemented or otherwise firmly attached to each side of the end of the strip, the open ends of the clamp being beaded over and tightly held against said strip on the inside 25 of said block by a wire loop passed through said beads. Instead of a single strip of elastic material, a plurality of strips may be detachably disposed between a pair of suspending members, or the suspending members 30 of a plurality of strips may be detachably connected to frames provided with hand grips. In a modified construction an elastic strip is transversely folded centrally of its length and clamped as above described to a transverse rod having eyes at 35 its ends engaged by hooks which engage the suspending members of a pair of exercising devices.

The accompanying drawings illustrate 40 several forms of exercising apparatus embodying my invention. In the drawings, Figure 1 is an elevation of a chest expander, and Figure 2 is a side view, to a larger scale, of one end thereof. Figure 3 is a section of 45 one end of the rubber strip illustrating a modification. Figure 4 is a similar view to Figure 1 illustrating another construction of chest expander, and Figure 5 is a section, to a larger scale, on the line X—X in Figure 4. Figure 6 is a part similar view to Fig. 4 illustrating a modification. Figure

7 is an elevation of a developer, and Figure 8 is a section, to a larger scale, on the line Y—Y in Fig. 7.

Referring to Figs. 1 and 2 of the drawings, in the chest expander therein illustrated, *a* is a long continuous strip of sheet rubber and *b* is a hand grip mounted on a U-shaped suspending member *c*. Each end of the rubber strip *a* is attached to the member *c* by a strip of metal *d* forming a clamp of width equal to that of the rubber strip. The clamp *d* is first folded round the member *c* and is then shaped to embrace two semi-cylindrical blocks *e* of rubber, wood or other suitable material cemented or otherwise suitably firmly attached to the end of the rubber strip *a* which is disposed between them. The open ends of the clamp *d* are beaded over as indicated at *f* and tightly held against the strip *a* on the inside of the block *e* by a loop of wire *g* passed through said beads. Instead of the semi-cylindrical blocks *e*, the ends of the rubber strip *a* may be moulded in the form of cylindrical blocks *e'* as shown in Fig. 3.

The clamp *d* is prevented from opening by the wire *g*, and has a very strong grip on the end of the rubber strip *a*, and, when good sheet rubber is employed, the construction forms a practically unbreakable chest expander.

Instead of a single strip of rubber or elastic material, I may employ, as shown in Figs. 4, 5 and 6, a plurality of strips separately attached by clamps *d* to a removable rod *h* which forms part of the suspending member *c* and is normally secured therein by nuts *j*. If desired, one or more of the strips may be removed as indicated in Fig. 4, the remaining strip or strips being spaced by distance pieces *k* threaded on the rod *h*. Or, as shown in Fig. 6, the ends of the strips *a* may be attached by clamps *d* to suspending members in the form of links *m* which are removably attached by spring hooks *n* to the removable rod *h* whereon they are spaced by distance pieces *k*, or the hooks *n* may be directly attached to a suspending member *c* such as is shown in Figs. 1 and 2.

Figs. 7 and 8 show an exerciser comprising strips of rubber *a* each attached at one end to suspending members *c* having hand grips *b* as described in connection with Figs. 1 and 2, and at their other ends by clamps *d* to links *m* which are attached by swivel hooks *p* to eyes *t* at the ends of a transverse

rod *q*. A clamp *d* attaches said rod to a long strip of rubber *r* which is folded transversely centrally of its length, the ends of the strip *r* being attached by clamps *d* to links *m* which can be engaged with wall hooks or the like. The folded centre portion of the rubber strip *r* embraces a cylindrical block *s* of rubber, wood or other suitable material loosely disposed within the fold, the clamp *d* binding the rubber strip around the block.

By my invention I provide exercising apparatus which is comparatively cheap to manufacture, is strong and much lighter than the usual type, and is very efficient in use.

What I claim and desire to secure by Letters Patent is:—

1. Exercising apparatus comprising a pair 20 of suspending members, a strip of elastic material disposed therebetween, cylindrical blocks fixed at the ends of said strip, clamps embracing said suspending members and said cylindrical blocks, the open ends of said 25 clamps being beaded over, and wire loops passing through said beads to retain the open ends of said clamps tightly against said strip on the inside of said blocks.

2. Exercising apparatus comprising a pair 30 of suspending members, a strip of elastic material disposed therebetween, cylindrical blocks fixed at the ends of said strip, clamps embracing said suspending members and said cylindrical blocks, the open ends of 35 said clamps being beaded over, and wire loops passing through said beads to retain the open ends of said clamps tightly against said strip on the inside of said blocks, said suspending members being provided with 40 hand grips.

3. Exercising apparatus comprising a pair of suspending members, a plurality of strips of elastic material detachably disposed therebetween, cylindrical blocks fixed at the

ends of said strips, clamps embracing said 45 suspending members and said cylindrical blocks, the open ends of said clamps being beaded over, and wire loops passing through said beads to retain the open ends of said clamps tightly against said strips on the in- 50 side of said blocks.

4. Exercising apparatus comprising a pair of suspending members, a strip of elastic material disposed therebetween, cylindrical blocks fixed at the ends of said strip, clamps 55 embracing said suspending members and said cylindrical blocks, the open ends of said clamps being beaded over, and wire loops passing through said beads to retain the open ends of said clamps tightly against 60 said strip on the inside of said blocks, the suspending members of a plurality of said strips being detachably connected to frames provided with hand grips.

5. Exercising apparatus comprising a pair 65 of suspending members, a strip of elastic material disposed therebetween, cylindrical blocks fixed at the ends of said strip, clamps embracing said suspending members and said cylindrical blocks, the open ends of 70 said clamps being beaded over, and wire loops passing through said beads to retain the open ends of said clamps tightly against said strip on the inside of said blocks, said strip of elastic material being transversely 75 folded, a cylindrical block within said fold, a clamp embracing a transverse rod and said fold and block, the open end of said clamp being beaded over, a wire loop passing through said beads to retain the open end of 80 said clamp against said strip on the inside of said block, eyes at the ends of said rod, connecting hooks, and a plurality of exercising devices attached by said hooks to said rod.

In testimony whereof, I affix my signature.

JAMES HUBERT.
